(57) **CLAIM**

The ornamental design for a wrench, as shown and described.

DESCRIPTION

FIG. 1 is a rear isometric view of a wrench showing my new design;

FIG. 2 is a front isometric view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a front elevation view thereof.

The broken lines in FIGS. 1 through 6 of the drawings depict environmental subject matter only and form no part of the claimed design.
